UNITED STATES PATENT OFFICE

99,485

DESIGN FOR A BRUSH

Frank R. Weber, Troy, N. Y., assignor to Mohawk
Brush Company, Albany, N. Y.

Application March 13, 1936, Serial No. 61,615

Term of patent 14 years

To all whom it may concern:

Be it known that Frank R. Weber, a naturalized citizen of the United States residing at Troy, in the county of Rensselaer and State of New York, has invented a new, original, and ornamental Design for Brushes, as shown in the accompanying drawing and described in the following specification.

In the drawing:

I claim:

The ornamental design for a brush, as shown.

FRANK R. WEBER.
